UNITED STATES PATENT OFFICE.

EDGAR R. STODDARD, OF DETROIT, MICHIGAN.

GREASE-CUP.

1,113,586.

Specification of Letters Patent. Patented Oct. 13, 1914.

Application filed September 21, 1912. Serial No. 721,681.

To all whom it may concern:

Be it known that I, EDGAR R. STODDARD, a citizen of the United States of America, residing at Detroit, in the county of Wayne 5 and State of Michigan, have invented certain new and useful Improvements in Grease-Cups, of which the following is a specification, reference being had therein to the accompanying drawings.

Grease cups comprising a screw cap and a base having a screwthreaded nipple for attachment to the part to be lubricated, are commonly formed with a hexagonal neck portion connecting the nipple and base for 10 the engagement of a wrench by means of which the base is turned and the nipple screwed into place.

To facilitate manufacture and decrease the weight, the base is commonly formed up 20 from sheet metal and in the process of forming, the metal is weakened where the nipple joins the neck, thus making the cup subject to breakage at this point when a wrench is applied to the hexagonal neck portion, and 25 if broken off, great difficulty is experienced in removing the nipple from the opening into which it has been screwed.

The object of this invention is to obviate these and other objections and to provide a 30 cup of minimum length, thus taking up a small space and decreasing the liability of breakage.

A further object is to cheapen the manufacture and to provide certain new and useful features in the construction, all as hereinafter set forth and more particularly pointed out in the claim, reference being had to the accompanying drawing in which—

Figure 1 is a side elevation of a grease cup 40 embodying the invention; Fig. 2 is a vertical section through the same; Fig. 3 is a side elevation of the base of the cup detached; and Fig. 4 is a transverse section on the line IV of Fig. 2.

The grease cup shown in the drawing comprises a cap portion 1 and a base portion 2, the cap being internally screwthreaded to engage an external screwthread 3 on the body of the base. The cap may be formed 45 in any desired manner and forms no part of this invention, said invention being embodied in the construction of the base 2 of the cup, which part comprises a cup-shaped body, the vertical annular flange or rim 4 of which is formed with the external 55 thread 3. The base has an inclined bottom

5, and an externally screwthreaded nipple 6 is formed integral with the bottom 5 axially thereof, to engage a screwthreaded opening in any machine or part to be lubricated and support the cup in position for use. The nipple 6 is formed hollow with an end wall 7 closing its lower end and this wall is provided with an axial discharge opening 8 for the escape of the lubricant 60 from the cup as the cap is turned down thereon and the grease pressed down into the base. The side wall of the nipple is preferably interiorly formed hexagonal in cross section, that is, it is formed with interior flat faces 9 for the engagement of a tool or bar (not shown) formed to fit therein for turning the base and screwing the nipple into the opening to which the cup is to be applied. 65

While the nipple is shown as interiorly formed hexagonal in cross section, it will be understood that it may be interiorly formed in any desired manner for the engagement therein of any suitable tool for turning the 70 cup. This interior formation of the nipple thus forms the sole means for turning the base in, placing the cup in position for use and the power is thus applied directly to the nipple in such a manner that there is no 75 possibility of breaking the cup. Should the cup be knocked off in use, breaking the body of the base from the upper end of the nipple, said nipple may be very readily taken out by applying the tool to the interior thereof. 80

A cup having a minimum over-all length is also provided by this construction thus making it applicable for use in a small space and greatly reducing the liability of its 85 being broken off in use.

As is the common practice in the manufacture of grease cups, these cups, for the purpose of cheapness, lightness and facility of manufacture, are formed from sheet metal by means of dies and it is obvious that 90 a base constructed as shown, may be formed up in this manner with the minimum number of separate operations.

Obviously, changes may be made in the form and construction of the parts of the 105 cup without departing from the spirit of my invention which consists in interiorly forming the nipple of a grease cup or like device, for the engagement of a tool therewith for turning the same, and I do not 110 limit myself to the particular construction or arrangement shown.

Having thus fully described my invention what I claim is:—

As a new article of manufacture, a base for grease cups stamped and drawn from sheet metal and comprising a conical bottom wall having a concentric depressed portion that is formed when drawn from said bottom to provide inner oblong facets and an outer cylindrical side, said depressed portion constituting a nipple which has an end wall provided with a small concentric opening, said end wall being disposed at right angles to the facets to limit the inward

movement of a tool placed in engagement with said facets, and the side walls of said nipple being relatively thicker than said bottom wall, whereby the outer cylindrical side can be screw threaded without materially weakening the nipple at the angles of the facets thereof.

In testimony whereof I affix my signature in presence of two witnesses.

EDGAR R. STODDARD.
